UNITED STATES PATENT OFFICE.

SIEGMUND FRÄNKEL, OF BIALA, AUSTRIA-HUNGARY.

BOTTLE-STOPPER.

1,163,520.

Specification of Letters Patent.

Patented Dec. 7, 1915.

Application filed May 7, 1914. Serial No. 837,021.

To all whom it may concern:

Be it known that I, SIEGMUND FRÄNKEL, subject of the Emperor of Austria-Hungary, residing at Biala, in the Kingdom of Galicia, in the Empire of Austria-Hungary, have invented certain new and useful Improvements in Bottle-Stoppers, of which the following is a specification, reference being had therein to the accompanying drawing.

10 The subject matter of the present application is a device adapted to be attached to any ordinary bottle having a flanged or projecting portion around the neck, such device being designed to enable liquids charged with 15 gas or sparkling liquids to be drawn off into glasses without causing loss of gas from the remainder of the liquid contained in the bottle.

20 The device is characterized by a member forming the housing and fitted with the clamping means for attaching the device to the neck, which member is fitted with a part furnished with the washer constituting the gas seal, the outlet conduit and the valve, 25 the said part being pressed against the top of the neck of the bottle by a plug screwed into an internally screw threaded portion of the housing.

30 A method of constructing the device according to the invention is illustrated by way of example, at Figures 1 to 4 of the accompanying drawing. These figures show respectively two side elevations at right angles to one another and two sections on the 35 lines A A of Fig. 1 and B B of Fig. 2. Fig. 5 shows the device in use, the section being taken on the line C C of Fig. 1.

40 The device comprises three essential portions namely: an outer housing *n* carrying the clamping means and forming the main support of the device, a closing piece *p* provided at the bottom with the plate or washer *v* forming the gas seal and having the outlet passage *q* and the valve *r* contained therein and a screw plug *m* which presses on the closing member *p* forcing it against the top of the neck of the bottle and screwing into an internally screw threaded portion at the top of the housing *n*.

45 50 In the method of making the device illustrated in the drawing, the housing *n* which forms the principal supporting member consists of a hollow cylinder provided with a slot *x*. The smallest diameter of this cylindrical housing *n* is somewhat greater than the diameter of the enlarged end *u* of an or-

dinary bottle. It is provided in two diametrically opposite points with downwardly projecting arms *a*, *a* in which are guided in such a way that they cannot rotate spin- 60 dles *h* carrying two curved cheeks *f*, pressed toward one another by flat springs *t*. The cheeks are intended to embrace the neck of the bottle beneath the enlarged projecting portion. 65

The upper portion of the housing *n* is provided with an internal screw thread for the reception of a screw plug *m*. In the housing *n* is located a cylindrical block *p* having a central perforation. This block is provided 70 with a washer *v* at the lower part, which washer is made of cork and is intended to form a gas and liquid tight seal. Through the washer *v* and the block *p* passes the outlet conduit *q*, which projects through the 75 slot *x* in the housing *n*. The inner orifice of the outlet conduit *q* which is situated below the washer *v* is provided with a double closure consisting of a bell-shaped valve *r*. This double closure is due to the lower part 80 of the valve *r*, having a closing disk *w* which comes against the end of the outlet passage *q*, while the upper edge of the bell valve *r* comes against the washer *v*. The valve *r* is carried by a spindle *z* which passes through 85 the outlet conduit *q* and extends upward, being pressed upward by the spring *d* located in the housing *c*.

In the upper portion of the housing *n* provided with internal screw thread, is screwed 90 a plug *m* the lower surface thereof acting against the block *p* guided in the lower portion of the housing *n*. The valve spindle *z* passes through a central bore of the plug *m*.

In order to reduce friction between the 95 plug *m* and the block *p* guided in housing *n* projections or feet *o* may be provided at the underside of the plug *m* coming against the upper surface of the block *p*.

100 The device is mounted and used in the following manner: The apparatus is attached to the neck of the bottle with the clamps *f*, provided with handles *h*, embracing the neck of the bottle beneath the enlarged portions *u*. After this the block *p* is pressed against the top of the bottle neck by screwing down the plug *m* and in this way the bottle is closed so as to be liquid and gas tight. When liquid is to be drawn from the bottle, this latter is turned into 110 the inclined position, as shown at Fig. 5, and the valve *r* is raised from the washer *v*

by pressing upon the knob at the end of the spindle z . This raises the valve from the opening at the end of the exit orifice, g , so that liquid can flow out through the outlet orifice under the pressure of the gas in the bottle. When the required quantity has been allowed to flow out, the valve r is released and comes back to the closing position under the pressure of the spring d , but the liquid remaining in the bell valve r , at the moment when the flow is cut off, is separated from that contained in the bottle and on turning the bottle back to the upright position the inner portion of the bell valve r being full, as seen at Fig. 4, a siphon-like closure is formed. The gas contained in the bottle after the bottle has been turned back into the upright position, is not only separated from the outer air, by the two sealing washers, in connection with the valve, but also by the liquid contained in the valve.

For the washer v , as also for the disk w , provided at the bottom of the bell valve r , a material free from rubber should be employed, preferably cork, and for the valve, the valve spindle and the outlet passage g , porcelain china or enameled metal should be

used, so that the liquid does not come into contact either with rubber or with any metallic part.

Having now particularly described and ascertained the nature of my said invention and in what manner the same is to be performed, I declare that what I claim is:

In a bottle stopper, a stopper housing, 35 downwardly extending arms for holding said housing against a bottle neck, an obturating block guided in said housing, a plug screwed in said housing and pressing against the said obturating block, a valve 40 stem guided in said block and said plug, a coil spring acting on the said valve stem, an outlet conduit extending through said obturating block and an upwardly turned bell shaped valve whose bottom acts against the outlet conduit and whose rim acts against the block so as to form a siphon like seal.

In testimony whereof I affix my signature in the presence of two witnesses.

SIEGMUND FRÄNKEL.
